UNITED STATES PATENT OFFICE.

COLUMBUS H. BISHOP, OF EL RENO, OKLAHOMA.

RAILWAY-TIE.

1,280,376.

Specification of Letters Patent.

Patented Oct. 1, 1918.

Application filed July 9, 1917. Serial No. 179,521.

To all whom it may concern:

Be it known that I, COLUMBUS H. BISHOP, a citizen of the United States, residing at El Reno, in the county of Canadian and State of Oklahoma, have invented certain new and useful Improvements in Railway-Ties, of which the following is a specification, reference being had to the accompanying drawings.

10 This invention relates to certain improvements in railway ties and it is an object of the invention to provide a novel and improved device of this general character which is adapted to have its major axes disposed longitudinally of a rail. It is also an object of the invention to provide a device of this general character including novel and improved means whereby a rail may be conveniently and effectively secured thereto and wherein a portion of said securing means serves to maintain transversely alined ties in substantially fixed relative position.

25 The invention consists in the details of construction and in the combination and arrangements of the several parts of my improved railway tie whereby certain important advantages are attained and the device is rendered simpler, less expensive and otherwise more convenient and advantageous for use, all as will be hereinafter more fully set forth.

The novel features of the invention will hereinafter be definitely claimed.

30 In order that my invention may be the better understood, I will now proceed to describe the same with reference to the accompanying drawings, wherein—

Figure 1 is a fragmentary view in side elevation illustrating a tie constructed in accordance with an embodiment of my invention and in applied position;

Fig. 2 is a fragmentary view in top plan illustrating a pair of transversely alined ties constructed and connected in accordance with an embodiment of my invention;

Fig. 3 is an end elevational view of the structure disclosed in Fig. 2 with the coacting rails in section;

50 Fig. 4 is a longitudinal vertical sectional view taken through a sleeper or pillow as herein included; and

Fig. 5 is a view in top plan of a base plate as herein embodied.

55 As herein embodied, a plurality of base plates 1, preferably rectangular in form,

are arranged end to end and have their major axes disposed longitudinally of a trackway. Each of the plates 1 at its transverse center is provided with a series of longitudinally spaced openings 2 and arranged at opposite sides of said openings 2 and equally spaced therefrom are the elongated slots 3 positioned at substantially the longitudinal center of the plate 1. Resting upon each of the plates 1 is a pillow or sleeper P and as is particularly illustrated in Figs. 3 and 4, the pillow comprises the longitudinally spaced bottom plates 4 connected by upstanding webs 5 arranged at the longitudinal marginal portions thereof. The upper end portions of the webs 5 are connected by the interposed horizontal plate 6 preferably integrally formed therewith and upon which a rail R is adapted to rest. The plate 6 is positioned below the upper margins of the webs 5 and the outer web 5 has its portion above the plate 6 provided with the inwardly directed lip or flange 7 which is adapted to overlie the outer flange 8 of the coacting rail R. The upper face or edge of the inner web 6 at substantially its longitudinal center, is provided with an upstanding pin 8 disposed through a longitudinally directed slot 9 formed in the end portion of an arm or lever 10. The inner extremity of the arm 10 is formed into the cam face 11 which is adapted to engage the web of the adjacent rail R as said arm 10 is swung at substantially right angles to the rail whereby it will be perceived that the arm 10 will coact with the flange 7 and maintain the rail in secure position upon the plate 6. The pillows P are adapted to be arranged in transversely alined pairs so that the outer end portions of the arms or levers 10 may assume an overlying relation, as particularly illustrated at 10 in Fig. 3, and be locked in such overlying relation through the medium of the bolts 12 or in any other manner which may be employed with equal facility and convenience.

Each of the plates 4 has depending therefrom at substantially its transverse center the longitudinally spaced pins 14 adapted to be seated within the openings 2 whereby the pillow is held against endwise or creeping movement. As is particularly illustrated in Fig. 1, it is preferred that an end portion of a pillow partly overlie the base plate 1 coacting with the adjacent pillow and in interlocking engagement through the

medium of a forward pin 14 and an opening 2 of the second plate. By this arrangement it will be at once self-evident that the plates 1 will be maintained in assembled relation 5 and against separating movement. I also find it of advantage to provide each of the webs 5 at substantially its longitudinal center with a depending pin 15 extending within a slot 3 to further assure the proper maintenance of the pillow upon the plate. It will 10 also be understood that the slots 3 and aligned series of openings 2 readily permit an adjustment of the pillow P longitudinally of said coacting plate 1 as the requirements 15 of practice may necessitate.

From the foregoing description, it is thought to be obvious that a railway tie constructed in accordance with my invention is of an extremely simple and comparatively 20 inexpensive nature and is particularly well adapted for use by reason of the convenience and facility with which it may be assembled, and it will also be obvious that my invention is susceptible of some change and modification 25 without material departure from the principles and spirit thereof and for this reason I do not wish to be understood as limiting myself to the precise arrangement and formation of the several parts 30 herein shown in carrying out my invention in practice.

I claim:

1. A supporting structure for a rail comprising plates arranged end to end and in a direction longitudinally of the rail, and pillows mounted upon the plates and upon which the rail is adapted to rest, said pillows serving to lock the plates in operative position.
- 40 2. A supporting structure for a rail comprising plates arranged end to end and in a direction longitudinally of the rail, pillows mounted upon the plates and upon which the

Copies of this patent may be obtained for five cents each, by addressing the "Commissioner of Patents, Washington, D. C."

rail is adapted to rest, said pillows serving to lock the plates in operative position, and 45 means for securing the rail to the pillows.

3. A supporting structure for a rail comprising plates arranged side by side and in a direction longitudinally of the rail, each of said plates having a series of aligned openings therein, pillows mounted upon the plates and upon which the rail rests and members depending from the pillows and insertible within the openings of the plate, each of said pillows resting upon a pair of 50 adjacent plates.

4. A supporting structure for the rails of a trackway comprising transversely aligned pillows upon which the rails are adapted to rest, the outer margins of the pillow being 60 provided with flanges to overlie the outer base flanges of the rails, levers pivotally engaged with the inner marginal portions of the pillows and serving to clamp the rails in applied position upon the pillows when 65 said levers are substantially at right angles to the rails and means for connecting the levers one to the other for maintaining the same in clamping action upon the rails.

5. A supporting structure for the rails of 70 a trackway comprising transversely aligned pillows upon which the rails are adapted to rest, said pillows being provided with means to engage the outer base flanges of the rails, levers pivotally engaged with the inner marginal portions of the pillows and serving to clamp the rails in applied position upon the pillows when 75 said levers are substantially at right angles to the rails and means for connecting the levers one to the other for maintaining the same in clamping action upon the rails.

In testimony whereof I hereunto affix my signature.

COLUMBUS H. BISHOP.
